(57) CLAIM

I, claim the ornamental design for a cosmetic compact case, as shown and described.

DESCRIPTION

FIG. 1 is a top plan view of a cosmetic compact case showing my new design.

FIG. 2 is a bottom plan view thereof.

FIG. 3 is a perspective top view thereof.

FIG. 4 is a front elevation view thereof.

FIG. 5 is a rear elevation view thereof.

FIG. 6 is a right side elevation view thereof.

FIG. 7 is a left side elevation view thereof.

FIG. 8 is a bottom rear perspective view thereof; and,

FIG. 9 is an enlarged partial perspective view thereof.

1 Claim, 2 Drawing Sheets
